UNITED STATES PATENT OFFICE.

PRESSE B. MITCHELL, OF HOMER, LOUISIANA.

COLLAPSIBLE BIT.

Application filed May 16, 1921. Serial No. 469,993.

To all whom it may concern:

Be it known that I, PRESSE B. MITCHELL, a citizen of the United States, residing at Homer, in the parish of Claiborne and State 5 of Louisiana, have invented certain new and useful Improvements in Collapsible Bits, of which the following is a specification.

This invention relates to drilling apparatus for oil wells and the like, and the primary object of the invention is to provide 10 an improved means for permitting a drill bit to be withdrawn for resharpening or the like, without necessitating the withdrawal of the drill stem from the hole, there- 15 by resulting in the saving of time and labor.

Another object of the invention is the provision of a novel collapsible drill bit, a novel drill stem for receiving the bit, and a novel means of associating the bit with the 20 stem in order to hold the bit firmly in its operative position during drilling.

A further object of the invention is to provide a novel carrier for the collapsible bit, which embodies means for collapsing the 25 bit in order to permit the withdrawal thereof from the stem, and means for normally urging the bit into an operative position when the bit reaches its lowermost drilling position in relation to its stem.

30 A still further object of the invention is to provide an improved collapsible drill bit apparatus of the above character, which will be durable and efficient in use, one that will be simple and easy to manufacture, and one 35 which can be placed upon the market at a reasonable cost.

With these and other objects in view, the invention consists in the novel construction, arrangement and formation of parts, as will 40 be hereinafter more specifically described, claimed and illustrated in the accompanying drawings, forming a part of this specification, in which drawings:

Figure 1 is a vertical longitudinal section 45 through the improved drilling apparatus.

Figure 2 is a similar view showing the bit in its collapsed position ready for withdrawal from the stem.

Figure 3 is a vertical longitudinal section 50 through the drilling apparatus taken at right angles to Figures 1 and 2.

Figure 4 is a fragmentary side elevation of the drilling apparatus showing a portion of the drill stem in section.

55 Figure 5 is a top plan view of the improved drilling apparatus.

Figure 6 is a bottom plan view thereof, showing the bit blades in their extended positions.

Figure 7 is a detail horizontal section 60 taken on the line 7-7 of Figure 2.

Referring to the drawings in detail, wherein similar reference characters designate corresponding parts throughout the several views, the letter A indicates the drill 65 stem; B, the bit; and C, the carrier for the bit.

The drill stem A includes the usual plurality of pipe sections, and the lowermost section has been designated by the numeral 70 10 and will be hereinafter referred to as the drill holder and will now be specifically described.

The tool holder 10 includes the elongated cylindrical body, which has its upper end 75 threaded for receiving the lower end of the adjacent pipe section, and the inner surface has its lower end flared or grooved at diametrically opposite points as at 11, for receiving the bit B as will be hereinafter more 80 fully described. The lower end of the holder 10 on each side of the flared portion 11 is provided with stop shoulders 12, which define therebetween a guide 13, for the bit B. The shoulders 12 form stops for the bit carrier C. The flared portions 11 of the tool 85 holder C are provided adjacent to their lower ends with stop shoulders 14, the purpose of which will also be described.

The bit B includes a pair of blades 15, and these blades, when in their extended operative positions appear similar to the ordinary fish tailed bit now in vogue. Each of the blades 15 include a longitudinally extended body having its outer edge provided with a 95 notch or shoulder 15' for engaging the shoulders 14 formed in the flared guide way 11. The outer edges of the blades 15 are sharpened, as at 16, to provide cutting edges, similar to the ordinary fish tail bit. 100 These blades 15 adjacent to their upper inner edges are provided with oppositely extending slots 17 which extend at an angle to the longitudinal center of the blade.

The carrier C for the bit includes upper 105 and lower elliptical shaped heads 18 and 19 which are connected together by a cylindrical shank 20. The lower head 19 is provided with an inwardly extending slot or recess 20', in which are adapted to fit the upper ends of the bit blades 15. This head carries a diametrically extending pivot pin 110

21, which extends through the upper ends of the blades and holds the same in position on the carrier. The opposite side walls of the slot or recess 20' adjacent to their lower 5 ends are flared as at 22, to permit the blades to swing on the pivot pin 21. The head 19 is also provided with the slot 23 opening out through the side walls of the head and communicating with the slot or recess 20', 10 and these slots 23 slidably receive a cross pin 24, which is mounted in the slots 17 formed in the blades 15. This cross pin 24 has its terminals secured to suitable guide strips 25, which are slidably mounted in 15 guide ways 26 formed in the opposite sides of the head 19. The connecting shank 20 of the heads 18 and 19 is also slotted diametrically as at 27, and this slot 27 slidably receives an upper cross pin 28, which is carried by the lower end of the actuating rod 29. By this arrangement, it can be seen that when the actuating rod is lowered, the bit blades 15 can be swung on the pivot pin 21, and thus be moved to their operative or in- 25 operative positions. The movement of the blades is accomplished by the pin 24 riding in the inclined slots 17. The upper head 18 and the connecting shank 20 are provided with a longitudinally extending bore, which 30 slidably supports the operating rod 29. The upper end of this rod 29 may be provided with a suitable head 30, in order that the same may be readily engaged by a grapple or the like, in order to permit the raising and lowering of the carrier and the bit. The shank 20, intermediate its ends, is provided with a reduced portion 31 around which is coiled an expansion spring 32, the lower convolution of which engages the 35 strips 25, while its upper convolution rests against a shoulder 33 formed by the reduced portion 31 of the shank. The spring normally tends to force the strips downwardly in the guides 26, and consequently swings 40 the bit blades 15 on the pivot pin 21 to their normal operative position through the medium of the pin 24 and the slots 17. The inner surface of the holder 10 at diametrically opposite points is provided with a pair 45 of longitudinally extending ribs 34, which communicate with the shoulders 12 at their lower ends. These ribs 34 are so disposed in relation to the elliptical heads 18 and 19 as not to interfere with the movement there- 50 of during the raising and lowering of the bit B. These ribs 34 are provided with longitudinally extending passageways 35. These passageways 35 also extend through the shoulders 12 and open out at the lower 55 end of the bit holder 10. The upper ends of these passageways 35 terminate in laterally extending passageways 36, which open into the interior of the holder 10 below the upper ends of the ribs 34. These passageways 60 65 form means for permitting water or the like

to be forced against or adjacent to the cutting edges of the blades 15, in order to remove or wash all débris from around the same.

In operation of the improved device, when 70 it is desired to lower a bit in position, the carrier C is lowered into the drill stem by means of the actuating rod 29. Inasmuch as the actuating rod 29 is then supporting the weight of the carrier C, the pin 24 will be 75 in its raised position at the upper ends of the slots 17, consequently holding the bit blades 15 in their folded position, as shown in Figure 2. When the carrier C reaches its lowermost position, the same will seat on the 80 shoulders 12, thus releasing the weight of the carrier from the rod 29, and the spring 32 engaging the upper ends of the strips 25, will force the pin 24 downwardly in the slots 17 to the lower ends thereof, thus 85 spreading the bit blades 15 and forcing the same to their operative positions. This will move the shoulders 15' formed on the blades 15 into engagement with the shoulders 14 formed in the passageways 11. This eliminates any movement of the blades into the holder during the drilling process. It also can be seen that owing to the shape of the heads 18 and 19, relative rotation between the carrier C, the bit B and the holder 10 90 will be absolutely precluded. When it is desired to raise the bit B, for any cause whatsoever, it is merely necessary to lower a grapple into the stem into engagement with the head 30 and start to raise the carrier. The 95 rod 29 will be first raised in the carrier for moving the pin 24 to the upper ends of the slots 17, which will move the bit blades 15 to their folded position, and the shoulders 15' out of engagement with the stop shoulders 14. Upon further upward movement of the rod 29, the carrier C and the bit B will be raised.

If so desired the bit B can be readily disconnected from the carrier simply by removing the pins 24 and 21, which are merely slipped into position. These pins are prevented from accidental displacement, when the carrier C is in its lower position by their engagement with the holder A and the 115 strips 25.

From the foregoing description, it can be seen that an exceptionally simple and durable drilling apparatus has been provided, in which a novel collapsible bit can be readily placed in or removed from position without necessitating the pulling of the entire drill stem.

Changes in details may be made without departing from the spirit or scope of this 125 invention; but,

I claim:

1. In a drill apparatus, a bit holder including a cylindrical body, spaced shoulders formed in the body adjacent to its lower end 130

- defining a restricted guide way, a bit carrier slidably mounted in the body arranged to seat on the shoulders, a pair of pivoted bit blades carried by the carrier and arranged 5 to extend exteriorly of the body, and means connected with the carrier for moving the blades on their pivot.
2. In a drill apparatus, a bit holder including a cylindrical body, shoulders formed 10 on the inner surface of the body adjacent to its lower end defining a guide way therebetween, a bit carrier slidably mounted in the body, a bit including a pair of pivoted blades, means pivotally securing the blades 15 to the carrier, shoulders formed on the outer longitudinal edges of the blades, and shoulders formed on the side walls of the guide way arranged to engage the shoulders formed on the bit blades when the same are in their 20 extended operative positions.
3. In a drill apparatus, a bit holder including a cylindrical body, spaced shoulders formed in the body adjacent to its lower end defining a guide way therebetween, the side 25 walls of the guide way having shoulders formed therein, a bit carrier slidably mounted in the body arranged to seat upon the first mentioned shoulders when the same is in its lowermost position in the body, a pair 30 of bit blades pivotally secured to the carrier and arranged to extend in the guide way, shoulders formed on the outer longitudinal edges of the bit blades arranged to engage the second mentioned shoulders, when the 35 blades are in their extended operative positions, an operating rod slidably carried by the carrier, and means operatively connecting the rod with the blades to permit the blades to be moved to their extended or 40 folded positions.
4. In a drill apparatus, a bit holder including a cylindrical body, a bit carrier slidably mounted in the body, a bit connected to the carrier including a pair of pivoted 45 blades, an actuating rod slidably mounted in the bit carrier, the bit blades having a pair of diagonal slots formed therein below the pivot point thereof, and a pin slidably mounted in said slots and connected to said 50 actuating rod, whereby upon movement of the rod, the blades will be moved to their extended or folded positions.
5. In a drill apparatus, a bit carrier including a cylindrical body, a bit carrier slidably mounted in the body, a bit including a pair of blades, means pivotally securing the blades at their upper ends to the lower end of the bit carrier, the bit blades having a pair of diagonally extending slots formed 55 therein below the pivot points thereof, a cross pin slidably mounted in the slots, an actuating rod slidably mounted in the carrier, means operatively connecting the cross pin with the rod, and spring means nor- mally urging the cross pin toward the lower 65 ends of said slots, whereby the bit blades will be normally held in an extended position.
6. In a drilling apparatus, a bit carrier including a body having a lower slotted end, a bit including a pair of blades having their upper ends inserted in the slotted portion of the body, a pivot pin extending through the body and the upper ends of the blades, the blades having oppositely 70 directed diagonal slots formed therein, an operating rod slidably mounted in the carrier, a cross pin slidably carried by the body and mounted in said slots, means connecting the cross pin with the actuating rod, and a spring coiled around the carrier and normally holding the cross pin in the lower 75 ends of the slots formed in the blades.
7. In a drilling apparatus, a bit carrier having a lower slotted end, a bit including a pair of blades mounted in the slotted end of the carrier, a pivot pin extending through the body and blades, the blades having a pair of oppositely extending diagonal slots formed therein, the opposite sides 80 of the carrier being provided with guide grooves, strips slidably mounted in the guide grooves, a pin carried by the lower ends of the strips and slidably mounted in the carrier and in the slots formed in the blades, a 85 longitudinally extending axially disposed operating rod mounted in the body, a second cross pin carried by the rod, the upper ends of the strips being connected to the second cross pin, and an expansion spring coiled 90 around the carrier and engaging the upper ends of the strips to normally urge the same and the first mentioned cross pin downwardly in relation to the carrier and blades. 95
8. In a drill apparatus, a drill holder, a drill bit carrier slidably mounted in the holder including a pair of elliptical shaped heads, and a connecting shank, the holder having oppositely disposed longitudinally 100 extending ribs formed therein, water channels formed in the ribs, opening out into the upper end of the holder and out through the lower end of the holder, and a drill bit including a pair of blades secured to the carrier. 105
9. In a drilling apparatus, a drill holder including a tubular body, a pair of shoulders formed on the inner surface of the body adjacent to the lower end thereof defining a guide way therebetween, diametrically opposed longitudinally extending ribs formed on the inner surface of the body and connected to the shoulders, the ribs and shoulders having fluid channels formed therein 110 opening out through the lower end of the body and into the body at the upper end thereof. 115
